ARRANGEMENT FOR THE REPRODUCTION
OF SOUND

Otto Kurt Kolb and David Whitehead Boston,
London, England, assignors to British Acoustic
Films Limited, London, England, a British com-
pany

Application March 19, 1942, Serial No. 435,332
In Great Britain April 4, 1941

7 Claims. (Cl. 179—100.3)

This invention relates to the recording and reproduction of sound with the use of sound film records. Picture films have been provided with one or more sound tracks and with a control track adapted to control amplification during reproduction, the control track being arranged within or substantially within the strip of the film occupied by the sprocket perforation holes at one edge of the film. Each of the two perforation strips of the film may be provided with such a control track.

According to the specification of British Patent No. 473,256, for example, the sound is recorded on the sound track under volume compression, and the amount of compression is registered by the control track or tracks, whilst in another case a film on which no control track has been recorded, i. e., a sound film recorded in the usual manner, is provided with such a control track or tracks.

In the reproduction of a sound film having a control track or tracks, a control current is derived from the control track or tracks by known photo-electrical means and this current controls the amplification of the reproducing amplifier. By this arrangement an expansion of the volume of the recorded sound is effected, the reproduction taking place through one amplifier channel.

Such an arrangement suffers from one drawback inasmuch as the maximum volume of undistorted sound reproducible is limited by the output capacity of the amplifier. This does not matter for dialogue and quiet musical pieces which make up the greater part of a sound accompaniment to a film, but it does place a limitation on the artistic interpretation of fully orchestrated musical passages and on special effects such as gunfire, running engines and the like.

The principal object of the present invention is to overcome this drawback by making use of a control current derived from a track or tracks in the sprocket hole line of the film to expand the volume range of the recorded sound in an improved manner by the use of one or more additional amplifier channels and so to increase the maximum volume of sound reproducible and to enhance the realism of the reproduced sounds.

A further object is to enable a control current to be derived from a control track or tracks located within the sprocket hole strip of film and to apply this control current to control a further reproducing amplifier or amplifiers additional to the main reproducing amplifier.

When one additional amplifier is provided, the output from this additional amplifier may be fed to the same loudspeaker or loudspeakers as those to which the output from the main amplifier is fed, or, it may be fed to additional loudspeakers. The arrangement may also be such that the low frequency sound currents from the main and additional amplifiers are all fed to the same low frequency loudspeaker whilst the high frequency currents are fed to separate loudspeakers.

The additional amplifier need not have the same frequency characteristics as the main amplifier, for example, it can be designed to deal with only a small range of frequencies, so that it may be of simple design and inexpensive construction. Moreover, the additional amplifier will preferably have a much greater power output than the main amplifier.

One feature of the invention resides in the provision of a control unit which is fed with current derived from the sound track proper on the film and also with current derived from the control track or tracks, and is so arranged as either to control all the amplifiers, including the main amplifier, or only to bring in one or more additional amplifiers as and when required.

The invention will now be described, by way of example, with reference to the accompanying drawing, wherein—

Figure 1 shows a diagram of one embodiment according to the invention wherein current from the sprocket hole control track controls both the main amplifier and an additional amplifier.

Figure 2 shows a diagram of a modification of the embodiment according to Figure 1 wherein only the additional amplifier is so controlled.

Figure 3 illustrates an embodiment of the circuit arrangement of the control unit shown in Figure 1, and

Figure 4 illustrates an embodiment of the circuit arrangement of the control unit shown in Figure 2.

Figure 5 shows a small portion of a film with the sound and control tracks thereon.

Referring to Figures 1 and 2, C represents the conventional light-sensitive cell and optical system and HA represents the normal head amplifier such as is fitted to present day sound film projectors. This amplifier is used to amplify photo-electrically produced sound currents obtained in well known manner by the cell C from the sound track on the film. This film may be like that shown in Figure 5, with a control track I between the sprocket holes at one side, and

the sound track 3 adjacent the sprocket holes at the same side of the film. C1 represents a light sensitive device, such as a photo-electric or selenium cell, which, together with its optical system, is used to produce a control current from the control track in the line of the sprocket holes on the film.

A further cell and optical system, C2, is also shown in dotted lines; this cell can be used to produce a control current from a second control track, if one is provided in the line of the second set of sprocket holes 2 on the film.

The outputs from the devices HA and C1 are fed to a collecting unit or fader F. Such a fader is provided for the manual adjustment of the sound film projector and also for facilitating changing over from one projector to another as is necessary at the end of each film reel.

In Figure 1, both the currents fed to the fader F are passed on to a control unit CU which controls both the main amplifier MA and an additional amplifier AA which in turn supply current to the loud speakers LS.

In Figure 2, it will be seen that the control current fed to the fader F is passed on to the control unit CU, as in Figure 1, whilst the sound track current is passed straight on to the main amplifier MA. A portion of this current from the head amplifier HA is, however, branched off from the connection between the fader and the main amplifier and fed to the control unit which thus only controls the additional amplifier AA.

In the arrangements shown in Figures 1 and 2 of the drawing the control unit CU brings in the additional amplifier AA at a certain amplitude of the control track and controls its amplification over a predetermined amplitude range. The outputs from the amplifiers MA and AA can be fed to the same or parallel loudspeakers LS; in fact, any desired arrangement of speakers can be employed.

Figure 3 illustrates an embodiment of the circuit arrangement of the control unit CU shown in Figure 1. A light beam modulated by the sound track 3 of Figure 5 is focussed on the light sensitive cell C, which may be a photo-electric cell or selenium cell, and the output of the cell C is fed to the head amplifier HA, the output from which is fed to the fader F. A light beam modulated by the control track 1 of Figure 5 is focussed on the light sensitive cell C1 and the output from this cell, after amplification if desired, is also fed to the fader F. From the fader it is passed on to the first valve V1 of the control unit.

It will be appreciated that the light beam focussed on the cell C1 consists of a modulated beam having a carrier frequency of 96 cycles per second, since at normal film feeding speed, 24 picture frames and therefore 96 sprocket holes will pass through the light beam every second. The transformer TR1, fed with the output of the valve V1, is therefore tuned to this frequency. The output from the transformer TR1 is rectified by a rectifier R1, smoothed by a filter circuit FC1 and fed through the secondary of a transformer TR2 to bias the control grid of a variable mu valve V2. The transformer TR2 is also connected to the fader F and fed with the output from the head amplifier HA. The output from the valve V2 is fed via a transformer TR3 to the main amplifier MA, of usual design, the output of which is thus controlled in dependence upon the output of the said valve.

The control grid of the valve V2 is biassed, as

for example by the battery B1, via a rectifier R2, the arrangement being such as to limit the maximum amplification gain of the valve. As a result, overloading of the valve with consequent distortion can be avoided and the valve can be made to handle currents only up to a desired maximum.

A portion of the control current is also fed via the rectifier R1, a second filter circuit FC2 and a further transformer TR4 to the control grid of a further valve V3, which is also of the variable mu type.

The variable mu valve V3 is also fed with a portion of the signal current from the head amplifier via the fader and the transformer TR4 and it is also biassed by the rectifier R3 and battery B2 in a similar manner to the valve V2 but to a different point on its working characteristic so that it only begins to function, for example, after the valve V2 has become loaded to its predetermined maximum. The output from the valve V3 is fed to a transformer TR5 and from there it is passed on to the additional amplifier AA, the output of which is thus controlled in dependence upon the output of the valve V3. The lines designated HT+ and HT- at their right hand ends represent the leads of the unit connected to the plus and minus terminals of a service of high tension electric current (not shown) as is usual in amplifier units.

Reference has already been made to the feature that the additional amplifier may be of simpler and less expensive construction than the main amplifier. In such a case it may occur that it gives rise to noticeable background noise during those periods when it is not reproducing sound passages, for example, when the main amplifier is reproducing only pianissimo passages. The valve V3 controlling the additional amplifier may therefore be provided with a switch or electrical relay, operated by hand or otherwise, to bring it into use only during those periods when it is under the control of the control track. For example, an automatically operating electrical relay is indicated by the reference RL in Figure 3. This relay has a coil in series with the anode of valve V3, and is arranged to close its contact as soon as the valve V3 begins to operate but to open when the valve is not operating. As shown by way of example and in dotted lines, the relay RL may be used to open and close the output circuit of the additional amplifier AA, leading to a loudspeaker LS.

Figure 4 illustrates an embodiment of the circuit arrangement of the control unit CU shown in Figure 2. The arrangement so far as the head amplifier HA, control cell C1 and fader F are concerned is the same as in Figure 3. However, in this embodiment, the signal currents from the head amplifier HA are fed straight on to the main amplifier MA via the fader F and, consequently, the main amplifier does not come under the control of the control unit. A part of the signal current from the head amplifier is branched off from the connection between the fader and the main amplifier and fed to the control unit, that is to say, the transformer TR2.

The control current is obtained as above by means of the valve V1, tuned transformer TR1, rectifier R1, filter circuit FC1 and transformer TR2 and applied to the control grid of the variable mu valve V2. This valve is also biassed by battery B1 via a rectifier R2 so as to limit the maximum amplification gain. The output from the valve V2 is fed to the transformer TR3 and

from there is passed on to the additional amplifier AA instead of to the main amplifier as in Figure 3. The circuit of valve V2 may also be provided with a switching relay RL if desired, as in Figure 3.

By the arrangement according to Figure 4, only the additional amplifier is controlled by the control track, and since this additional amplifier may have a maximum output several times that of the main amplifier, it will be appreciated that it is possible to employ it for the reproduction of special effects, fully orchestrated musical pieces and the like, with great advantage.

Whilst in the foregoing specific embodiments of the invention the control of the amplifiers depends upon the amplitude of the control track, it will be understood that the control can be effected by means of different frequencies carried by the control track.

We claim:

1. Apparatus for reproducing sound from film records such as are provided with at least one control track in line with the sprocket holes of the film in addition to the sound record track thereon, said apparatus comprising means for deriving a sound current from said sound record track, means for deriving a control current from said control track, a main amplifier and an additional amplifier, a control unit including a first amplifying valve, means for applying said control current to the grid of said valve, a transformer tuned to a frequency corresponding to the rate at which the sprocket holes in the film which are in line with the control track pass through the apparatus means for applying the output of said valve to said transformer, a rectifier connected to the output of said transformer, a second valve of a type adapted for variably controlled amplification, means for applying the output of said rectifier as a grid bias control to a grid circuit of said second valve, means for applying sound current to the input of said second valve, and means for applying the output of said second valve to the input of said additional amplifier.

2. Apparatus for reproducing sound from film records such as are provided with at least one control track in addition to the sound record track thereon, said apparatus comprising means for deriving a sound current from said sound record track, means for deriving a control current from said control track, a main amplifier and an additional amplifier, a control unit including a first amplifying valve, means for applying said control current to the grid of said valve, a transformer and means for applying the output of said valve to said transformer, a rectifier connected to the output of said transformer, a second valve of a type adapted for variably controlled amplification, means for applying the output of said rectifier as a grid bias control to a grid circuit of said second valve, a constant voltage source and means including a rectifier for applying a constant voltage therefrom to said grid circuit whereby the gain of said second valve may be limited, means for applying sound current to the input of said second valve, and means for applying the output of said second valve to the input of said additional amplifier.

3. Apparatus for reproducing sound from film records such as are provided with at least one control track in addition to the sound record track thereon, said apparatus comprising means for deriving a sound current from said record track, means for deriving a control current from

said control track, a main amplifier and an additional amplifier, a control unit including a first amplifying valve, means for applying said control current to the grid of said valve, a transformer and means for applying the output of said valve to said transformer, a rectifier connected to the output of said transformer, a second valve of a type adapted for variably controlled amplification, means for applying the output of said rectifier as a grid bias control to a grid circuit of said second valve, means for applying sound current to the input of said second valve, means for applying the output of said second valve to the input of said main amplifier, a third valve also of a type adapted for variably controlled amplification, means for applying grid bias control from the output of said first valve to a grid circuit of said third valve, means for applying sound current to the input of said third valve, and connections for applying current from the output of said third valve to the input of said additional amplifier.

4. Apparatus for reproducing sound from film records such as are provided with at least one control track in addition to the sound record track thereon, said apparatus comprising means for deriving a sound current from said record track, means for deriving a control current from said control track, a main amplifier and an additional amplifier, a control unit including a first amplifying valve, means for applying said control current to the grid of said valve, a transformer and means for applying the output of said valve to said transformer, a rectifier connected to the output of said transformer, a second valve of a type adapted for variably controlled amplification, means for applying the output of said rectifier as a grid bias control to a grid circuit of said second valve, means for applying sound current to the input of said second valve, means for applying the output of said second valve to the input of said main amplifier, a third valve also of a type adapted for variably controlled amplification, means for applying grid bias control from the output of said first valve to a grid circuit of said third valve, means for applying sound current to the input of said third valve, and connections for applying current from the output of said third valve to the input of said additional amplifier, a constant voltage source and means including a rectifier for applying a constant voltage therefrom to the grid circuit of said second valve whereby the gain of said valve may be limited, and means for applying a grid bias from such a constant voltage source also to the grid circuit of said third valve.

5. Apparatus for reproducing sound from film records such as are provided with at least one control track in addition to the sound record track thereon, said apparatus comprising means for deriving a sound current from said record track, means for deriving a control current from said control track, a main amplifier and an additional amplifier, a control unit including a first amplifying valve, means for applying said control current to the grid of said valve, a transformer and means for applying the output of said valve to said transformer, a rectifier connected to the output of said transformer, a second valve of a type adapted for variably controlled amplification, means for applying the output of said rectifier as a grid bias control to a grid circuit of said second valve, means for applying sound current to the input of said second valve, and means for applying the output of said second valve to the input of said additional amplifier.

second valve to the input of said main amplifier, a third valve also of a type adapted for variably controlled amplification, means for applying grid bias control from the output of said first valve to a grid circuit of said third valve, means for applying sound current to the input of said third valve, and connections for applying current from the output of said third valve to the input of said additional amplifier, a constant voltage source and means including a rectifier for applying a constant voltage therefrom to the grid circuit of said second valve whereby the gain of said valve may be limited, and means for applying a grid bias from such a constant voltage source also to the grid circuit of said third valve, the value of the bias applied to the grid of said third valve being such that its coming into operation is delayed until after the second valve has been loaded to a substantial extent.

6. Apparatus for reproducing sound from film records such as are provided with at least one control track in addition to the sound record track thereon, said apparatus comprising means for deriving a sound current from said sound record track, means for deriving a control current from said control track, a main amplifier and an additional amplifier, a control unit including a first amplifying valve, means for applying said control current to the grid of said valve, a transformer and means for applying the output of said valve to said transformer, a rectifier connected to the output of said transformer, a second valve of a type adapted for variably controlled amplification, means for applying the output of said rectifier as a grid bias control to a grid circuit of said second valve, means for applying sound current to the input of said second valve, means for applying the output of said second valve to the input of said

additional amplifier, and an electrical relay in the output circuit of said second valve adapted to bring said additional amplifier into operation only when current is flowing in the output circuit of said second valve.

7. Apparatus for reproducing sound from film records such as are provided with at least one control track in addition to the sound record track thereon, said apparatus comprising means for deriving a sound current from said record track, means for deriving a control current from said control track, a main amplifier and an additional amplifier, a control unit including a first amplifying valve, means for applying said control current to the grid of said valve, a transformer and means for applying the output of said valve to said transformer, a rectifier connected to the output of said transformer, a second valve of a type adapted for variably controlled amplification, means for applying the output of said rectifier as a grid bias control to a grid circuit of said second valve, means for applying sound current to the input of said second valve, means for applying the output of said second valve to the input of said main amplifier, a third valve also of a type adapted for variably controlled amplification, means for applying grid bias control from the output of said first valve to a grid circuit of said third valve, means for applying sound current to the input of said third valve, and connections for applying current from the output of said third valve to the input of said additional amplifier, said connections including an electrical relay adapted to bring said additional amplifier into operation only when current is flowing in the output circuit of said third valve.
